(57) **CLAIM**

We claim the ornamental design for an electrical equipment mounting frame, as shown and described.

DESCRIPTION

FIG. 1 is an isometric view of an electrical equipment mounting frame showing our new design;

FIG. 2 is a front view of the FIG. 1 mounting frame;

FIG. 3 is a right side view of the FIG. 1 mounting frame;

FIG. 4 is a left side view of the FIG. 1 mounting frame;

FIG. 5 is a rear view of the FIG. 1 mounting frame;

FIG. 6 is a top view of the FIG. 1 mounting frame; and,

FIG. 7 is a bottom view of the FIG. 1 mounting frame.

The broken lines shown represent unclaimed subject matter and form no part of the claimed design.
